SPARK TIMER FOR HAMMERS

Carl L. Charles, Winnetka, Ill., assignor to Gas
Tool Patents Corporation, a corporation of
Delaware

Application April 5, 1937, Serial No. 135,185

14 Claims. (Cl. 123—146.5)

This invention relates to internal combustion percussive hammers, and more particularly to spark timers therefor.

One feature of this invention is that it provides means for varying the time of commencement of ignition; another feature is that it provides means for varying the duration of flow of ignition current; another feature of this invention is that it provides improved mounting means for the ignition points; yet another feature of this invention is that a mounting is provided sealing the points from a contact with inflammable vapors; still another feature of this invention is that means is provided for varying the duration of flow of ignition current in accordance with the temperature of the hammer, which means may be either manual or automatic; other features and advantages of this invention will be apparent from the following specification and the drawings, in which:

Figure 1 is a vertical elevation, partly in section, of an internal combustion percussive tool embodying this invention; Fig. 2 is a fragmentary sectional view of the hammer shown in Fig. 1; Fig. 3 is an elevation of the timer housing and mounting; Fig. 4 is a view, partly in section, along the line 4—4 of Fig. 3; Fig. 5 is a detailed sectional view of a modified form of timer; Fig. 6 is a detailed sectional view of a timer particularly designed for varying the duration of flow of ignition current; and Fig. 7 is a sectional view of a timer having means for automatically varying the timing.

The internal combustion hammer or percussive tool illustrated herewith has a cylinder 10 having a piston hammer 11 freely reciprocal therein and adapted to impart blows to a tool at the bottom of the hammer through the anvil 12. A piston return spring assembly 13 urges the piston upwardly. The hammer is provided with a charge forming device 14 provided with a tank adapted to contain a liquid fuel, a carburetor, and the necessary manifold passages to enable a combustible charge to be drawn into the chamber 15 beneath the piston and thereafter transferred to the combustion chamber 16 above the piston through the passage 17, in accordance with known two-cycle engine practice.

The hammer is provided with an ignition system including a spark plug 18 and a timer 19. An ignition unit including a battery or other source of current and a buzzer operated spark coil is connected, in accordance with known practice, to the hammer through a cable having a high tension and a low tension circuit therein. The

high tension circuit is connected to the spark plug by the wire 20, while the low tension circuit is connected to the timer by the wire 21, thus enabling the timer to control ignition by control of the current flow therein. It will be noted that the piston 11 is provided with a cam surface 22 adapted to actuate, upon reciprocation of the piston, a cam follower or plunger in the timer 19.

The hammer shown herein as one embodiment of this invention is of the same fundamental type as that shown in Mould Patents Nos. 1,868,754 and 1,997,072, for example, and the general mode of operation of the hammer is fully described therein.

In order to secure efficient operation of an internal combustion engine it is, of course, necessary to have the high tension spark or ignition means initiated at a particular time with respect to the reciprocation of the piston in the cylinder. Too early ignition results in knocking, over heating, and other troubles; and too late ignition results in poor combustion efficiency, loss of power, slower action of the hammer, and the like. The point at which the spark should be initiated also varies somewhat in accordance with the temperature of the hammer, and it is preferable to provide means for adjusting the action of the timer in this respect to vary the timing of the ignition.

Where ignition of the "make" type is used, as disclosed on this particular embodiment of the invention, high tension sparks continue to flow across the spark plug electrodes as long as the points in the timer are closed. This is, of course, a drain on the battery and therefore it is preferable not to have ignition current flow any longer than necessary. In order to start a hammer of this type, however, it is necessary to have a much longer time of ignition current flow than that which will effectively operate the hammer after it is warmed up. It is thus also desirable to provide means, as here disclosed, for shortening the duration of flow of ignition current as the hammer warms up. It will be seen that proper control of the timing of the hammer thus includes one or both of the two elements discussed above: the first, the point or time of initiation of ignition; and second, the duration of ignition current flow.

In the particular timer illustrated in Figs. 2 to 4, the cylinder 10 is provided with an opening 23 therethrough transverse to the axis of the cylinder. A sleeve member 24 is held therein by studs 25 tapped into the cylinder wall or a boss provided therefor. Within the sleeve 24 is a lon-

itudinally movable plunger 26 having a roller 27 on the inner end thereof adapted to contact the cam surface 22 on the piston. A coil spring 28, axially disposed with relation to the plunger, 5 biases or urges it against the piston, so that reciprocation or movement of the piston in the cylinder effects longitudinal movement of the plunger 26.

The plunger 26 has movably mounted therein 10 and coaxial therewith a second longitudinally movable plunger 29. The inner end of the plunger 29 is provided with a stop 30 adapted to contact a shoulder on the plunger 26 to prevent outward movement of the second plunger with respect to the first. A coil spring 31 surrounds the second plunger and lies between a shoulder thereon and a shoulder on the plunger 26, yieldingly urging the second plunger outwardly with respect to the first plunger. It will be thus seen 15 that the two plungers may telescope within each other to the extent of the space provided between the stop 30 and the roller 27, so that the plunger 26 may continue to move outwardly as a result of movement of the piston even though 20 the second plunger 29 has ceased outward movement.

A pair of cooperating ignition points 32 and 33 are provided. The point 33 is adjustably mounted on the end of the plunger 29 and adapted 25 to be moved toward and into contact with the point 32 upon movement of the first plunger 26. This point 32 is mounted on a member 34 passing through insulated washers 35 and 36 on each side of an opening 37 in the housing 38. The outer end of the member 34 is threaded, 30 and a nut 39 is provided for locking the member in place.

The points 32 and 33 are operatively connected 35 in the low tension ignition circuit to control ignition as a result of a change of relationship, that is, from open to closed relationship, or vice versa. The point 32 is insulated from the hammer body and connected to the wire 21 through the connecting lug 40. The point 33 is grounded 40 to the hammer through the plungers in contact with the cylinder wall. It will be noted that the timing of the hammer may be varied by moving the point 33 toward or away from its cooperating point to vary the instant of initiation of ignition with respect to movement of the piston. The lug 40 engages a flattened portion of the member 34 and acts as a wrench for holding the member while the nut 39 is drawn up tight. It is prevented from falling out of place when the 45 nut is slightly loosened by the shoulder portions engaging the washer.

The springs providing the necessary bias on the two plungers are here shown as nested coil springs in substantially coaxial relationship. The 50 spring 31 is of lighter construction than 28, so that during the latter part of the movement, when the plunger 26 is pushing against both springs, there will not be undue wear on the cam surface. The particular arrangement shown 55 has been found to be very rugged as well as efficient. The plungers and springs are so arranged that the terrific vibration of the hammer when in operation causes little or no wear and difficulty with the parts. The springs particularly have been found to stand up much better 60 than flat springs of various types originally used in the hammers.

Shims may be inserted between the outer or 65 plate portion of the member 34 and the wall of the cylinder, so that when the studs 25 are

drawn up the final position of the cam follower with respect to the piston and cam surface thereon will be affected thereby. The presence of these shims serves two purposes. They might be inserted or removed to change the initiation point, to compensate for wear of the cam surface or cam follower, or both. Adjustment here also assures the minimum over travel of the point 33 necessary to avoid intermittent separation of the point from vibration and spring surge during the period it is desired to have them stay closed. That is, if the points just barely touch and then stay in that position for an appreciable time interval, surges in the springs 28 and 31, vibrations in the body of the hammer, or both, 1 may cause the points to separate momentarily and thus interrupt ignition. Where there is considerable over travel of the first plunger 26 the spring 31 is put under sufficient tension to insure that the points 32 and 33 remain in contact during the interval that contact is desired. In the particular embodiment of this invention illustrated in Fig. 2, for example, there is about forty-seven thousandths of an inch difference 2 between the low point and the high point on the 2 cam surface of the piston, so that the plunger 26 moves about this distance during reciprocation of the piston. The points are preferably set with an initial gap of only about five thousandths of an inch, so that there is thus about forty-two thousandths of an inch over travel to insure maintenance of the points closed.

In order to facilitate original adjustment of the shims in the shop or in the field, the outer face 31 of the plunger 26 is arranged to be about 35 forty-five thousandths of an inch from the outer face 32 of the flat portion of the member 34 when the member 26 abuts the shoulder 33. In order to insure proper initial position of the plunger and points with respect to the piston it is then only 40 necessary to bring the high point of the cam surface on the piston adjacent the roller 27, so that the plunger 26 is moved as far to the left as it would be in operation, and then to insert or move shims beneath the flat portion of the member 45 24 until the outer surface 31 of the plunger 26 is flush with the surface 32. This makes a very convenient assembly or field adjustment, and one which is independent of wear on the cam surface or roller.

The housing 38 is so constructed and arranged 50 as to seal the points from atmosphere. This is a desirable feature, since it prevents any chance of a sparking at the points igniting combustible vapors which may be present in the air about the 55 hammer. The tank in the charge forming device 14 contains a supply of relatively volatile inflammable fluid, usually gasoline, which fluid is open to atmosphere through the tank filler cap, the air intake to the carburetor, and the like. 60 Portions of unburned charge are frequently exhausted from the cylinder, moreover, through the exhaust port 41. Priming of the hammer when it is cold in order to facilitate starting also increases the gasoline vapors present in the atmosphere immediately about the hammer. When these hammers are used near gas mains, in mines, or the like, combustible vapors or gases may be 65 present which are of an even more explosive nature. Enclosing the points in a housing which 70 seals them from atmosphere, therefore, is a safety feature tending to prevent undesired ignition of these vapors.

In the modification of this invention illustrated 75 in Fig. 5, the longitudinally movable plunger 42

has mounted in the end thereof a point 43 adapted to cooperate with a point 44 mounted in a second longitudinally movable plunger 45 slidably journaled in the housing 46. Coil springs 47 and 48, which may be duplicates, are provided urging both plungers in the direction toward the cylinder. A reinforcing beam 49 extends across between studs similar to 25.

In the particular modification being described 10 the entire housing 46 is insulated from the cylinder of the hammer by the appropriate insulating washers 50 and 51, so that the connecting lug 52 is not insulated from the housing. When reciprocation of the piston moves the plunger 42 15 to the left, the point 43 makes contact with the point 44 and continued outward motion of the plunger 42 is absorbed by movement of the second plunger 45.

In this particular modification a sleeve 53 is 20 shown as threaded into the opening in the wall of the cylinder 10. The base plate or sleeve member 54 is bolted to the cylinder in the same manner as was previously described in connection with Fig. 3. The outer end of the threaded sleeve 25 53 provides a stop or shoulder against which the plate 54 is bolted. Rotation of the threaded sleeve 53 prior to drawing down the studs holding plate 54 on the cylinder thus adjusts the point of initiation of ignition with respect to reciprocation 30 of the piston. It is to be understood that the spacing between the points may be adjusted, if desired, by insertion or removal of shims between the housing 46 and the base plate 54.

Another modification is illustrated in Fig. 6. 35 wherein the timer is particularly designed to enable variation of the duration of ignition current in accordance with temperature changes in the hammer. A longitudinally movable plunger 55 is adapted to be moved through contact with 40 the cam surface on the piston, as previously described, and has mounted on the outer end thereof of the point 56 adapted to cooperate with the second point 57 of the pair of points. This latter point is mounted on a movable member 58 slidably mounted in a bearing 59. A coil spring 60 biases the movable member and point 57 toward the cylinder, but an adjustable stop 61 prevents movement beyond a certain desired position, so that the points 56 and 57 are separated during 45 the major portion of the movement of the piston.

The movable member 58 also has mounted thereon a point 62 adapted to cooperate with a point 63 mounted on a movable means here shown as a double leaf spring 64. This spring urges the 55 point 63 into contact with the point 62, and causes it to remain in contact therewith during initial movement to the left of the member 58. A stop against which the spring 64 abuts is here shown as a stud 65 threaded into an insulating bushing 60 60 in the housing 66 and manually adjustable through rotation of the outer knob or head.

In this particular embodiment, as the piston rises in the cylinder and compresses the charge 65 above it, the plunger 55 moves outwardly as a result of its contact with the gently sloping cam surface on the piston until, at the desired instant, the point 56 contacts the point 57 and completes the low tension circuit to energize the spark coil 70 and ignite the charge. As the piston continues to rise the plunger 55 carries the member 58 outwardly with it, the points 62 and 63 still maintaining a close relationship. After a predetermined amount of movement of the member 58, 75 however, the spring 64 contacts the end of the

stop screws 65 and further outward movement of the plunger and member causes the points 62 and 63 to change their relationship and separate. This breaks the ignition circuit, even though points 56 and 57 are still closed.

The modification shown and described in the preceding paragraphs gives full control of the timing, and is economic of battery power. Adjustment of the stop screw 61 varies the point at which ignition is initiated with respect to the 10 stroke or reciprocation of the piston; and rotation of the stop screw 65 varies the length of time during which ignition current flows. This latter adjustment is so arranged as to be easily operable at any time, in order that the length of 15 current flow may be reduced as the temperature of the hammer rises. When the hammer is being started cold the screw 65 is backed off so that there is a relatively long sparking period to take advantage of delayed ignition. As the hammer 20 warms up the stop screw may be turned further inward to vary the period during which the circuit is closed so that the ignition current, generally supplied by a light dry battery, shall not be 25 any greater drain on the battery than necessary.

A modification designed to provide automatic control of the period during which ignition current flows is illustrated in Fig. 7. As described in connection with Fig. 6, a longitudinally movable plunger 67 and a movable member 68 carry 30 points 69 and 70, respectively, which points are adapted to be closed at a desired instant to complete the ignition circuit and initiate sparking across the electrodes of the plug. The outer end of the member 68 also carries a point 71 adapted 35 to cooperate with a point 72 normally in contact therewith.

The point 72, however, is here shown as mounted on a movable support 73 which comprises a pair of metals having different coefficients of expansion. The member 73 thus assumes different free positions in accordance with the temperature of the hammer. The bimetallic movable element is so arranged that when the hammer is cold the point 72 follows the point 71 outwardly 40 and remains in contact therewith throughout a relatively long interval. As the hammer warms up the free or unbiased position of the movable mounting means 73 moves further towards the cylinder, so that the points 71 and 72 remain in 45 contact for a shorter interval of piston movement. The period of ignition current flow is thus automatically regulated to effect easy starting and battery economy when the hammer is warmed 50 up and working.

While I have shown and described certain embodiments of my invention, it is to be understood that it is capable of many modifications. Changes, therefore, in the construction and arrangement 55 may be made without departing from the spirit and scope of the invention as disclosed in the appended claims, in which it is my intention to claim all novelty inherent in my invention as broadly as permissible, in view of the prior art.

I claim:

1. Ignition apparatus for an internal combustion percussive hammer having a cylinder, a piston freely reciprocable therein, said piston being adapted to impart impacts to a tool, and means for supplying said cylinder with a combustible charge, including: an ignition system for igniting said charge, said system including a pair of cooperating ignition points for controlling said ignition; a longitudinally movable plunger actuated by reciprocation of said piston through con- 75

- tact with a cam surface thereon and effective to move one of said points toward the other; a coil spring opposing said movement; a second longitudinally movable plunger so constructed and arranged as to permit further movement of said first plunger after said points have come into contact; and a second coil spring opposing the movement of said second plunger.
2. Apparatus of the character claimed in claim 10 1, including a housing sealing said points from atmosphere.
3. Ignition apparatus for an internal combustion percussive hammer having a cylinder, a piston reciprocable therein, said piston being adapted to impart impacts to a tool, and means for supplying said cylinder with a combustible charge, including: an ignition circuit for igniting said charge; means actuated by movement of said piston for closing said circuit; a second means actuated upon further movement of said piston for breaking said circuit; and means for adjusting the period during which said circuit is closed to vary the timing of said ignition.
4. Ignition apparatus for an internal combustion percussive hammer having a cylinder, a piston reciprocable therein, said piston being adapted to impart impacts to a tool, and means for supplying said cylinder with a combustible charge, including: an ignition circuit for igniting said charge; a longitudinally movable plunger actuated by movement of said piston through contact with a cam surface thereon; a pair of cooperating points in said circuit adapted to contact each other upon movement of said plunger to close said circuit; a second pair of cooperating points in said circuit, normally biased together, adapted to separate upon further movement of said plunger to break said circuit; and means for adjusting the period during which said circuit is closed to vary the timing of said ignition.
5. Ignition apparatus for an internal combustion percussive hammer having a cylinder, a piston freely reciprocable therein, said piston being adapted to impart impacts to a tool, and means for supplying said cylinder with a combustible charge, including: an ignition circuit for igniting said charge; a longitudinally movable plunger actuated by movement of said piston through contact with a cam surface thereon; a pair of operating points in said circuit adapted to contact each other upon movement of said plunger to close said circuit; a second pair of cooperating points in said circuit; a movable member having mounted thereon one of each of said pairs of points; movable means on which the other of said second pair of points is mounted, said means being so constructed as to maintain said second pair of points in contact upon initial movement of said member effected by closing of said first pair of points by said plunger, but to cause said points to separate upon further movement of said member.
6. Ignition apparatus for an internal combustion percussive hammer having a cylinder, a piston freely reciprocable therein, said piston being adapted to impart impacts to a tool, and means for supplying said cylinder with a combustible charge, including an ignition circuit for igniting said charge; means actuated by movement of said piston for closing said circuit, said means including a pair of cooperating points; means actuated upon further movement of said piston for breaking said circuit, said means including a second pair of points; mounting means

for one of said second points tending to maintain said points in close relationship; and variable stop means for varying the instant of separation of said second pair of points.

7. Ignition apparatus for an internal combustion percussive hammer having a cylinder, a piston reciprocable therein, said piston being adapted to impart impacts to a tool, and means for supplying said cylinder with a combustible charge, including an ignition circuit for igniting said charge; a longitudinally movable plunger actuated by movement of said piston through contact with a cam surface thereon; a pair of cooperating points in said circuit adapted to contact each other upon movement of said plunger to close said circuit; a second pair of cooperating points in said circuit; a movable member having mounted thereon one of each of said pairs of points; spring mounting means for the other of said second pair of points, said spring means tending to maintain said second pair of points in contact during movement of said member effected by closing of said first pair of points by said plunger; and manually adjustable stop means to vary the instant at which movement of said spring means is arrested to separate said second pair of points.

8. Ignition apparatus for an internal combustion percussive hammer having a piston therein, including: a pair of cooperating ignition points having operative connections for initiating flow of ignition current upon contact thereof, at least one of said points being movable; actuating means for moving said movable point into and out of contact with the other in accordance with the reciprocation of said piston in the hammer; and means for automatically adjusting the duration of flow of said ignition current in accordance with the temperature of the hammer.

9. Ignition apparatus for an internal combustion percussive hammer having a cylinder, a piston freely reciprocable therein, said piston being adapted to impart impacts to a tool, and means for supplying said cylinder with a combustible charge, including: an ignition circuit for igniting said charge, said circuit including a pair of cooperating ignition points for initiating current flow upon contact thereof; actuating means for moving one of said points into and out of contact with the other in accordance with the reciprocation of said piston, said actuating means being operable by contact with said piston; and means for breaking said circuit after it has been closed for a desired period, said means automatically varying the length of said period in accordance with the temperature of the hammer.

10. Apparatus of the character claimed in claim 9, including a second pair of points in said circuit.

11. Apparatus of the character claimed in claim 9, including a second pair of points in said circuit and a thermally responsive element upon which one of said second pair of points is mounted.

12. Ignition apparatus for an internal combustion percussive hammer having a cylinder, a piston reciprocable therein, said piston being adapted to impart impacts to a tool, and means for supplying said cylinder with a combustible charge, including: an ignition circuit for igniting said charge; a longitudinally movable plunger actuated by movement of said piston through contact with a cam surface thereon; a pair of cooperating points in said circuit adapted to contact each other upon movement of said plunger

to close said circuit; a second pair of cooperating points in said circuit; a movable member having mounted thereon one of each of said pairs of points; a thermally responsive movable means on which the other of said second pair of points is mounted, said means being so constructed as to maintain said second pair of points in contact for a desired period during movement of said member effected by closing of said first pair of points by said plunger, whereby said period is automatically varied in accordance with the temperature of the hammer.

13. Ignition apparatus for an internal combustion percussive hammer having a cylinder, a piston freely reciprocal therein, said piston being adapted to impart impacts to a tool, and means for supplying said cylinder with a combustible charge, including: an ignition system for igniting said charge, said system including a pair of co-

operating ignition points for controlling said ignition upon a change of relationship thereof, at least one of said points being movable; a longitudinally movable plunger actuated by reciprocation of said piston, said plunger having one of said points mounted thereon; means whereby said plunger may continue further movement after said points have come into contact; and means for mounting said plunger in said hammer, said means being adjustable to move said plunger toward or away from said piston.

14. Apparatus of the character claimed in claim 13, wherein said mounting means for the plunger has a point thereon adapted to register with a cooperating point on said plunger when said plunger is moved to its farthest outer position by said piston.

CARL L. CHARLES.
